UNITED STATES PATENT OFFICE.

CLARENCE H. FREDERICK, OF KENOSHA, WISCONSIN, ASSIGNOR TO THE SIMMONS MANUFACTURING COMPANY, OF KENOSHA, WISCONSIN, A CORPORATION OF WISCONSIN.

BED FABRIC.

1,152,500.

Specification of Letters Patent.

Patented Sept. 7, 1915.

Application filed June 20, 1914. Serial No. 846,295.

To all whom it may concern:

Be it known that I, CLARENCE H. FREDERICK, a citizen of the United States, residing in the city of Kenosha, county of Kenosha, and State of Wisconsin, have invented certain new and useful Improvements in Bed Fabrics, of which the following is a specification.

My invention relates to improvements in bed fabrics and refers more particularly to that type of bed fabric which is built up of a series of longitudinal link chains arranged in parallel relation and connected together by means of cross-links engaging the links of the longitudinal chains.

The salient objects of my invention are, to provide an improved form of wire link fabric in which the cross-links of the fabric are positively positioned without danger of slipping or interference with the other members of the fabric; to provide an improved construction by which the tension transmitted by the cross-links is prevented from separating, stretching or bending the longitudinal links of the fabric; to provide an improved construction in which the links are of comparatively simple form and cheaply and economically manufactured, and, in general, to provide an improved bed fabric of the type referred to.

My invention consists in the matters hereinafter described and more particularly pointed out in connection with the accompanying drawings, in which—

Figure 1 is a plan view of my improved bed fabric; Fig. 2 is a section of Fig. 1 taken on the line 2—2; and Fig. 3 is a fragmentary section taken on the line 3—3 of Fig. 1.

The wire fabric shown is of the general type shown and described in U. S. Letters Patent No. 758,920, issued to O. R. Hunt May 3, 1904.

Referring to the drawings, it will be seen that the fabric as a whole is constructed of longitudinal chains each made up of a series of similarly formed links 4 hooked into engagement with one another, these links being connected together by cross-links 5. Each of the longitudinal links 4 is symmetrically formed with an eye 6 at one of its ends, this eye being engaged by the free ends of the other end of the adjacent link which are bent around the eye into hook form, as shown very clearly at 7 in Fig. 3. A short distance above the hook end of each of the

longitudinal links the latter is given a complete twist, as shown at 8, and between the twist and the extremity of the hook of the link the two companion wires forming the hook end of the longitudinal link are separated from one another to form a four-sided space 9, the opposite sides of this space providing bights 10 which are engaged by the cross-links 5 of the fabric.

Upon a careful inspection of the construction of my improved fabric it will be manifest that with this method of forming the longitudinal links it is impossible for the cross-links to slip or become displaced, since they are positively retained in position by the sides of the bights 10 formed in the ends of the longitudinal links, and, obviously, it is equally impossible for the eyes of the longitudinal links to become displaced. The spreading of the open ends of the longitudinal links due to the tension of the cross-links 5 is obviated by the twist 8, which also prevents any possible tendency for the cross-links to travel up the longitudinal links toward the eyes 6. It will be seen also that the links of the fabric are of extremely simple form and can be constructed with a comparatively small number of operations of the automatic machinery by which these longitudinal link chains are constructed, and, in addition, the form of the link is such that every part of the wire is effective for performing its particular function and there is no waste of material caused by unnecessary bends or complicated shapes.

The fabric may be folded both transversely and longitudinally and when so folded it occupies comparatively small compass and there is also little danger of the links snarling or catching when the fabric is to be again unfolded in its normal flat position.

Although I have described and shown what I consider to be a preferred embodiment of my invention, it is obvious that certain changes may be effected in the details of the fabric without departing from the spirit of my invention, and in my case I do not desire to be limited in the use of my invention except as specified in the appended claims.

I claim—

1. A wire link bed fabric, comprising a plurality of similarly formed longitudinal link chains arranged in substantial paral-

lelism, each link being made from a piece of wire bent upon itself intermediate its ends to form the eye of the link, and the two ends of the wire being bent to form a pair of 5 hooks at the other end of the link, said hooks engaging the eye of the adjacent link of the chain, the link being given a longitudinal twist adjacent its hook ends and being provided with opposing bights adjacent the 10 hooked ends, and cross-links engaging said bights and connecting together the adjacent longitudinal chains of the fabric.

2. A wire link bed fabric, comprising a plurality of similarly formed longitudinal 15 link chains arranged in substantial parallelism, each link being made from a piece of wire bent upon itself intermediate its ends to form the eye of the link and the two ends of the wire being bent to form a pair of 20 hooks at the other end of the link, said hooks engaging the eye of the adjacent link of the chain, said link being given a longitudinal

twist and provided with a pair of opposed bights intermediate the twist and its hooked end, and cross-links engaging said bights 25 for tying the longitudinal chains together.

3. A wire link bed fabric, comprising a plurality of similarly formed longitudinal link chains arranged in substantial parallelism, each link being made from a length 30 of wire bent upon itself intermediate its ends to form the end eye of the link, the two ends of the wire being formed into hooks, said hooks engaging the end eye of the adjacent link of the chain, the link having a longitudinal twist intermediate the length of the link and a pair of opposed bights contiguous to said twist, and cross-links engaging said bights for tying said chains together.

CLARENCE H. FREDERICK.
